UNITED STATES PATENT OFFICE.

PETER W. FULFORD AND CHARLES STECHER, OF CHICAGO, ILLINOIS.

PAIL-EARING MACHINE.

No. 864,529.

Specification of Letters Patent.

Patented Aug. 27, 1907.

Application filed April 8, 1907. Serial No. 366,989.

To all whom it may concern:

Be it known that we, PETER W. FULFORD and CHARLES STECHER, citizens of the United States, and both residents of Chicago, Cook county, Illinois, have

5 invented new and useful Improvements in Pail-Earing Machines, of which the following is a full, clear, and exact description, such as will enable others skilled in the art to which it appertains to make and use the same.

10 Our invention relates to improvements in mechanisms for applying ears to pails, and has special reference to improvements in machines for double seaming or otherwise fastening ears in and upon lard pails and the like.

15 The object of our invention is to provide a machine of the class mentioned which shall quickly and accurately secure the ears upon metal pails of the kind referred to.

20 A further and particular object of our invention is to provide a single automatic machine which shall perform all of the operations of punching and flanging a pail, and of applying and fixing previously prepared ears thereon.

25 Our invention consists in pail holding means, in combination with a pair of punching and flanging dies to operate on a pail held by said means, ear-feeding means, a pair of ear clenching, seaming, or fastening dies for securing an ear in or upon the pail and means for operating said pairs of dies successively.

30 Our invention also consists in the combination of a set of dies adapted to punch holes in the opposite sides of a pail, with another set of dies adapted to fix ears in said holes, and means for feeding a pail; first, to the punching dies; and then to the ear affixing dies, and 35 for thereafter removing the pail from the paths of said dies.

Our invention includes the combination of the aforesaid earing mechanisms proper with means for automatically feeding previously formed ears thereto.

40 More particularly, our invention comprises a pair of coacting punching dies for punching the side of a pail and forming a flange around each hole thus made; a pair of coacting finishing dies for inserting the ears in the holes formed by said punching dies and fastening 45 the ears therein, and means for presenting a pail to said dies successively.

Our invention also comprises two sets of punching and earing dies, as mentioned, each set mounted upon a slide and adjustable toward or from each other to accommodate pails of various sizes.

Our invention further consists in the relatively adjustable punching and earing mechanisms mentioned, in combination with an automatic ear-feeding device for each and means for operating said mechanisms simultaneously.

Our invention further consists in novel details of con-

struction and in arrangements and combinations of parts; all as hereinafter fully described and particularly pointed out in certain of the claims.

Our invention will be more readily understood by 60 reference to the accompanying drawings forming parts of this specification.

Figure I is a front elevation of a pail earing mechanism embodying our invention, one side thereof being shown in section; Fig. II is a top plan view of the 65 mechanism illustrated in Fig. I; Fig. III is a cross section on the line X—X of Fig. I; Fig. IV is a detail view (upon an enlarged scale) of the ear feeding mechanisms; Fig. V is a detail sectional view (upon an enlarged scale) of the dies, illustrating the operation of the punching 70 and flanging dies; Fig. VI is a view similar to Fig. V illustrating the operation of the finishing dies, the same being shown almost closed; Fig. VII is a cross section upon the line Y—Y of Fig. I, the same being shown upon an enlarged scale; Fig. VIII is a detail 75 end view of a die holding block; Fig. IX is a detail sectional view of a portion of the side of a pail with the ear secured thereto; and Fig. X is a similar view of the ear before being secured to the pail.

As here shown in its preferred form our invention 80 consists in a machine adapted to apply previously prepared ears to lard pails and the like. It is adapted to operate automatically when once freed and set into motion by its driving clutch, and it is readily adjustable to different sizes of pails. As will be better understood later, our machine is adapted to apply different kinds of ears to pails of the class mentioned, provided the necessary changes are made in the dies, which latter are in every case conformed to the particular kind of ear, which is preferred by the user or 85 purchaser of the pails. The principal parts or elements of our machine are, first, two pairs of coacting punching and flanging dies adapted to perforate and flange the sides of a pail, preparatory to the reception of ears;—second, two pairs of coacting ear affixing or 90 fastening dies, preferably arranged beneath the first mentioned dies; third, means for actuating the punching and ear affixing dies successively; fourth, two ear feeding mechanisms which coact with the ear affixing dies; and fifth, suitable means for feeding a pail to 100 said dies in succession; the operation being such that the sides of the pail are first punched and flanged and then the ears are placed in the holes of the pail and are there fastened, after which the eared pail is removed or expelled to make place for another pail.

One pair of punching dies and one pair of earing or ear affixing dies are preferably placed in one frame or carrier and the other pair are placed in another frame or carrier. These frames, or carriers, are adjustable upon the main frame of the machine, and it will be 110 readily seen that in this way we adapt the machine for use with pails of different sizes. As a means of

operating the die members which are in substantial abutment at the meeting ends of the two frames, or carriers, we preferably employ a single vertically movable operating member which is common to all 5 said members. This part is arranged to first actuate the punching die members, and then the earing die members. The outer members of the dies are operated by cams that are suitably mounted upon respective frames or carriers. The ear feeding devices are 10 preferably mounted upon respective carriers, likewise the means for operating certain members thereof. This arrangement of parts permits all of the moving members to be driven from a single power shaft. This shaft, as well shown in Fig. I, is in gear connection 15 with the die operating cams referred to, and the shaft itself carries a large cam which operates the single member employed in connection with the inner members of the pairs of dies. The cam on said shaft performs a further office of operating the pail chuck, or 20 carrier, being adapted to the necessary two stage downward movement of said chuck, by which the pail is fed to the punching and ear affixing dies in succession. The ears are held in magazines which constitute parts of the ear feeding mechanisms, and are released from 25 their magazines one at a time by a simple mechanism which is preferably actuated from the reciprocating pail chuck. The driving mechanism is such as to be thrown into operation by a treadle and is released automatically at the completion of a single cycle of 30 movements, in other words, at the moment when the pail chuck returns to its normal, or receiving position. As will be better explained hereinafter the ears are fed upward to the earing dies at the instant that the pail descends, and the pail at such time provides or forms 35 walls or guides which aid in retaining the ears and in leading them into proper positions in the pail and between the dies. In the machine illustrated, the ears are applied to the inner side of the pail and are thrust outwardly through the openings therein, to be seamed 40 into place by the dies. In other words, the ears are of a kind that require handling in this way, and hence, in being inserted are moved upwardly within the pail. But it should be understood that our invention is not limited to the structures which are used in thus 45 feeding the ears, as pail ears of some other kinds are applied from the outside of the pail and slight mechanical changes in the machine shown are sufficient to adapt it to such usage. The modification required in this regard is so obvious that we have not deemed 50 it necessary to illustrate the modified structure. These statements apply also with reference to the faces or configurations of the coating dies, which, as before stated, necessarily take their shapes from the kinds or styles of ears to be used. To avoid confusion and 55 misunderstanding it is explained that in the particular machine herein shown it is necessary to substitute other chuck plates or parts when the machine is adjusted for a different sized pail, and likewise, the common actuating member of the inner dies is replaced 60 by another of greater or less width, according as the carriers, or frames, are moved apart or more nearly brought together.

Referring now to the drawings for a thorough understanding of the details of construction, it will be seen 65 that the main frame or bed, A, of the machine is sup-

ported on legs, B, and is provided with ways, C, in or on its top. These ways extend from end to end of the frame or bed and in them we arrange the two die carriers or frames, D, D. These occupy reverse positions, in other words the dies are arranged in the adjoining 70 or adjacent ends of the frames, D, providing a group of dies substantially at the center or vertical axis of the main frame. For adjusting the frames, D, D, we employ screws, d', and after being adjusted they are fastened in place upon the ways by means of clamping 75 blocks, d'', provided on the main frame, A. The main frame is provided with a vertical bearing, 21, coincident with the vertical axis of the machine to receive the single or common actuating member of the dies, before alluded to. The die frames or carriers, D, D, are 80 adjusted with relation to the bearing, 21, and the degree of separation thereof is determined by the diameter of the pail to be operated upon.

The carriers, D, D, are identical in construction, and this is true also of the parts carried thereby. A detailed description of one will serve for both. It will be noted that the dies are arranged at slight inclination upon carriers, D, when tapered pails are to be eared; but this is modified in the case of machines adapted to the earing of cylindrical pails, in which case the die 90 members operate upon lines which are parallel with the top of the main frame. In either case the frame is provided with upright sides, 9, equipped with guiding ribs or gibs, 10, and is also provided with a bracket portion or standard, 1, at its inner end, the latter part containing the inner members of the dies. 7 and 8 are two slides held by the guide ribs, 10, and movable toward and from the blocks or standard, 1. The slides contain anti-friction rollers, 15 and 16 in their outer ends and are operated by cams, 17 and 18, the latter 100 fixed upon a vertical shaft, H.

Referring to Figs. 1, 2 and 7, it will be noted that pins, 7''' and 8''', extend from the slides 7 and 8 through slots in the sides of the carrier, D. To these pins we attach the retracting springs, 7^a and 8^a, which 105 hold the slides back against the respective cams 17 and 18. The inner end of each slide, 7, 8, is equipped with a block, 11, having a separable clamping portion, 11'. These blocks are threaded and contain the dies, 12 and 13, respectively, having threaded shanks which 110 are adjustable in the blocks, 11. After being thus adjusted the dies are fastened or clamped by means of the parts, 11'. It should be noted that the upper or punching die member, 12, is hollow, and that the inner end, 7', of the slide, 7, is likewise hollow, affording a tube 115 or passage through which the blanks or waste cut from the pails are discharged. The blanks fall from the passage, 7', through holes, 7'', 8'', and D', provided in the slides 7 and 8, and the carriers, D; as well shown in Fig. 1, clogging of the machine being thereby 120 avoided.

A gap or opening is left between the outer dies and the bracket or standard, 1, to receive the side of a pail. The inner die members 2 and 3 are arranged in the bracket 1, having bearings therefor in alignment with 125 the outer die members. The face or end of the die member, 2, properly conforms to the face of the die member, 12, the two together being adapted to punch an opening in the side of the pail and thereafter flange the metal around the opening, as well shown in Fig. 5. 130

The die member, 3, likewise conforms to the outer member 13, the two dies being adapted to co-act in the insertion and clenching of an ear, 50, in the flanged opening of the pail, as well shown in Fig. 6.

5 The die members 2 and 3 are provided with beveled ends, 2' and 3', that engage the double wedge block or device, 19, which latter is the single operating member hereinbefore referred to. Upon the upward stroke of this member it engages the upper die member, 2, and 10 drives the same outwardly toward the die, 12, and upon the downward stroke of the common actuating member, 19, the die 3, is driven outward to meet the complementary member, 13.

The lower outer face of the bracket 1 is provided with 15 a recess, 3'', which communicates with the cylindrical opening that contains the die member, 3. The die member, when retracted, leaves space in the end of the bearing to receive an ear, 50. In the part, D, directly beneath the recess referred to is a pocket, 30, to hold an 20 ear, 50, preparatory to the feeding thereof to the dies. Above the pocket, 30, is an upright spring or small bracket, 45, between which and the bracket 1, the ear is guided when raised to the ear affixing or seaming dies, 3-13.

25 The ears are supplied to the pocket, 1, by an ear feeding mechanism, P. This mechanism comprises the magazine, P', and the more steeply inclined discharge end or spout portion P'' thereof, together with an escapement device which is operated from the pail chuck, 30 as more fully described hereinafter. The tube or chute, P'', is attached to the carrier, D, and moves therewith. At its lower end it communicates with a cross slot, 30', through which the ears pass to the pocket, 30.

35 For lifting the ears into position between the dies, 3 and 13, we employ a plunger, 40, arranged in guides 41, on the lower part of the casting or frame, D. This slide is actuated by a lever, J, pivoted on the frame D, and operated by a cam, 44, on the shaft H, the latter engaging an antifriction roll, 43, on the end of the lever, J.

40 As a convenient means of supporting the shaft, H, we provide the frame D, with the depending bracket, E, and arrange the shaft bearings, H' and H'' in the parts D and E. The bracket, E, also has a horizontal bearing, E', for the main power shaft, F, and as shown in 45 Fig. 1, said power shaft is connected with the shaft H, by bevel gears, I-I'. The gear, I', is slidably fixed on the shaft, F, and hence shaft, H, remains in connection with the shaft, F, when the member, D is moved or adjusted on the main frame.

50 The end of the shaft, F, extends through a bearing in or on the main frame and by means of collars is fixed against longitudinal movement in the main frame. This is desirable and practically necessary as the shaft 55 carries the cam, L, which operates the central mechanisms of the machine and it must needs maintain its position in the plane of the central vertical axis of said mechanisms, as more fully explained hereinafter.

As best shown in Figs. 1, 2, 5 and 6, the two carriers D, 60 with their complements of dies and operating members are placed end to end in such manner that the inner dies thereof stand very close together, with only a small space between them. As little movement of the frames, D, is required in the adjustments from large to small 65 pails, or from small to larger sizes we find it possible to

retract the members 2-2, and the members 3-3, by springs, 6, which extend between and join respective pairs thereof. The members 2 and 3 are provided with cross pins, 4; these extend through slots, 5, in the brackets, 1, and are joined by said springs 6. The 70 slots limit the retractive movement of the members by the springs, and the pins prevent the turning of the die members in the brackets or blocks, 1-1.

20 is a vertical connecting rod or plunger arranged in the fixed bearing 21, and having a cross slot in its top 75 wherein the lower end of the member 19, is secured by a pivot pin, 20'. The lower end 19' of the member, 19, is rounded and loosely fits within the plunger, 20, so that it may swing or yield slightly at its upper end, as sometimes required, to follow the die members 2 and 3, when 80 the frames or carriers are carelessly adjusted. The upper end of the member, 19, is provided with beveled shoulders, 19^a, to engage and drive apart the die members, 2-2, and is provided with straight shoulders, or edges, 19^b, to drive between said members, 2, and positively hold them apart in the manner shown in Fig. 5, i. e. at the instants that they receive the pressure of the outer die members, 12-12. In like manner the lower part of the member 19 is provided with beveled shoulders, 19^c, terminating in straight or flat portions, 19^d, 90 operative to project the two members 3-3, and lock them momentarily, to receive the pressure of the opposed dies 13-13. The member 19 is operated by means of the cam L on the shaft F, said cam being provided with a groove, M, which contains the roller 22 on 95 the lower end of the plunger 20. As best shown in Fig. 3 the groove has portions, m, and m', for forcing the member to the extreme upper position and for drawing it down to the lowest position, respectively. Between the parts, m and m', is a portion m'', which is a portion 100 of a true arc, and which has the effect of causing the member, 19 to pause between the die members 2 and 3 during its downward stroke. The portion m''' is a longer arc which restores the member 19 to its central position toward the end of the cycle of the machine and 105 maintains the member 19 in this position during the first part of the next cycle, i. e., during the time required to expel a completed pail from the machine, and during the time required to lower the next pail to the 110 punching dies.

It will be obvious that a skilful operator would be able to invert a pail and place it between the punching dies of the machine and then at the right instant drop or force the pail down into position to be operated upon by the earing dies. We, however, prefer to 115 equip the machine with positive means for accomplishing the movement of the pail and for expelling or throwing out the completed pail. These means comprise a chuck preferably divided into two parts, O-O, on opposite sides of the box or bracket, 1. These plates 120 carry suitably positioned gages, O', for holding the pail centrally over the dies. Means may be provided for fastening the pail on the chuck plate, but it is usual for the operator to simply place and hold the pail thereon and remove it therefrom when finished and the machine is so shown in the drawing. The chuck plates are carried by vertically reciprocating rods, 25, which extend down through the frame, A, and are fastened in the yoke, 26. The yoke itself is guided by studs, 27, depending from the frame A, and is operated 130

by the cam wheel, L, said yoke having a lug or roller 28, which enters a cam groove, N in said wheel. This groove is laid out in such manner that as the cam wheel is rotated in the direction of the arrow the chuck is lowered to position the pail between the punching dies, 2—12, and is momentarily held in such position, after which the chuck is further lowered and held with the pail before or between the dies, 3—13. Further rotation of the cam, occurring after the dies 3—13 have opened, elevates the chuck and thereby expels the completed pail. In the drawings, the parts are shown in the positions which they occupy when the machine is stopped.

As before stated, the ears are fed to the finishing dies automatically. These ears are held in chutes, P, one of which is secured to each of the frame members D. Suitable mechanism is provided whereby one ear at a time is fed to each finishing die at the proper time. To this end, we form the chute in two portions P' and P'', and place the feeding mechanism preferably at the juncture thereof. The portion P' should be kept practically full of ears while the machine is in operation. It has sufficient pitch to feed the ears forward by gravity and constitutes the magazine, while the portion P'' constitutes the chute proper and has a greater inclination in order that an ear, when released, will descend with such rapidity as to carry it to the proper position in a pocket 30 formed in the frame D beneath the inner earing die. The feeding or releasing mechanism referred to comprises a double bell crank lever having two short arms 31 and 32 provided with pins or lugs 33 which project into the path of the ears, and a long arm 34, which projects into the path of the vertically reciprocating chuck plate O. When the chuck plate O is in elevated position the bell crank lever is in the position shown in Fig. III, but as the chuck plate, O, descends a spring 35 actuates the bell crank lever, throwing the same into the position shown in Fig. IV which lowers the arm 34 and raises the arm 31, permitting an ear to advance into engagement with the lug 33 on the arm 32. As the chuck plate O rises to the position shown in dotted lines in Fig. IV it engages the arm 34 and raises the same. This raises the arm 32 and releases the ear which immediately drops into the pocket 30, the lug on the arm 31 in the mechanism having descended to hold back the other ears in the magazine. Thus it will be seen that at each reciprocation of the chuck plate an ear will be fed to each of the earing mechanisms. In as much as the ear magazines are attached to the frames of the earing mechanisms they will also move therewith when the same are adjusted for different sized pails, hence, as both feed mechanisms are operated by a single arm 34, some provision must be made for the adjustment of these parts. To this end the arms 31 and 32 are formed upon a sleeve 36 feathered upon the shaft which carries the arm 34. However, instead of providing the one feed mechanism for the two magazines X X we may form them independently, each pair of levers 31 and 32 having its own arm 34 for engagement with the chuck plate, for operating the same.

As previously stated the frames or carriers, D, with their brackets, E, are adjustable with relation to the main shaft, F, and this adjustment is made without

varying the position of the cam L because the shaft is held against longitudinal movement, by the bearing shown in dotted lines in Fig. I. At a point outside of the frame the shaft bears a driving pulley G, and the members of the clutch R, whereof S is the pressure arm. The clutch is shown in disengaged condition, in which condition it is held by the stop pin Q', provided on the frame and adapted to be retracted by means of the treadle Q. When the pin is thus retracted the clutch parts which are on the pulley G and the shaft F, respectively, connect the pulley to the shaft and thereby start the machine into action.

The operator having depressed the treadle Q immediately releases the same, thereby restoring the pin Q' to the path of the lug or cam on the movable member of the clutch R; hence, the clutch will be disengaged from the pulley on completing a single revolution. It will be noted that the pinions, I and I' are of the same size; hence, a single revolution of the shaft F, imparts a single revolution to the cam, L, and also to the two shafts, H—H, causing single reciprocations of the dies. These being the conditions, it will be readily seen that the operations of all parts of the machine are very easily timed, as the only parts requiring adjustment, for time, are the cams L, 17, 18, and 44.

The operations and functions of the individual members of the machine will be fully understood from the foregoing, and hence, the operation of the machine as a whole will be clear to the reader. Nevertheless, to insure a complete understanding of the invention we will now briefly describe its use and the principal operations performed by it.

Figs. 3 and 4 show that ears are released from the magazines by the rise of the chuck; hence, at the moment that the treadle is depressed to start the machine, the pockets 30 will contain ears 50. A pail held on the chuck O as shown by dotted lines in Fig. 3, will be lowered between the pairs of dies 2—12 by the first downward movement of the chuck. At this instant, the member 19 rises between the die members 2—2, projecting them against the inner sides of the pail in time to meet the outer members 12, which are then forced in by their cams 17. The dies punch the sides of the pail and form flanges of the shape required to fit the kind of ear which is in use. The waste is ejected through the openings 7' and 7" as before stated. The next step in the operation consists in the retraction of the dies 12 and 2 and for an instant preceding the movement of the dies 13—13, the wedge member, 19, remains in its mid position. During this time the chuck lowers the pail until the openings therein are directly opposite the dies 3—13. Then the plungers 40 ascend and lift the ears into the spaces between the sides of the pail and the members 3—3. In actual operation the descent of the pail and the ascent of the plungers 40, occur at so nearly the same instant that the sides of the pail help to form outer wall guides for the ears, the latter reaching their positions at the moment that the holes in the pail come into alignment with the dies. At such time the wedge member 19 is forcibly drawn down and projects the die members 3—3, thereby driving the ears through the holes in the pail; and instantly there-

- after the clenching, swaging, or seaming dies, 13—13, strike the outer sides of the pail and complete the fastening of the ears therein. This having been done the dies 13 and 3 are retracted, the wedge member 5 ascending to its mid position, and the plungers 40 fall into their lower positions ready to receive ears from the magazines. As the latter operations are taking place the cam L, operating through the medium of the yoke 26, elevates the chuck O, expelling the pail 10 and operating the ear feeding mechanism to supply ears to the pockets or plungers, 40. Thereupon the shaft F having completed its revolution is stopped by the action of the automatic clutch throwing device Q'. It will be readily understood that the function of the 15 pail as a guide for the ears is preserved when the ears are fed upwardly against the outer sides thereof as before mentioned. It will also be obvious that various modifications not herein specifically mentioned will readily suggest themselves to one skilled in the 20 art and for this reason we do not confine the invention to the specific structure and sequence of operations herein shown and described.
- Having thus described my invention I claim as new and desire to secure by Letters Patent:
- 25 1. In a machine of the class described, a pail holding device, in combination with a pair of punching dies to make an ear hole in a pail, ear feeding means and a pair of ear affixing dies, substantially as described.
2. In a machine of the class described, a pail holding 30 device, in combination with a pair of punching dies to make an ear hole in a pail, ear feeding means, a pair of ear affixing dies and means for operating said pail holding device and for operating said pairs of dies successively, substantially as described.
3. In a machine of the class described, the combination 35 of a set of dies adapted to punch holes in the opposite side of a pail with another set of dies adapted to fix ears in said holes and means for feeding a pail first to the punching dies and then to the ear affixing dies and thereafter 40 removing the pail from the paths of said dies, substantially as described.
4. In a machine of the class described, the combination 45 of a set of dies adapted to punch holes in the opposite side of a pail with another set of dies adapted to fix ears in said holes, ear feeding means, and means for feeding a pail first to the punching dies and then to the ear affixing dies and thereafter removing the pail from the paths of said dies, substantially as described.
5. In a machine of the class described, two pairs of dies 50 adapted to punch holes in the opposite sides of a pail, in combination with another set of dies adapted to fix ears in said holes, ear feeding means and a pail feeding device or chuck, substantially as described.
6. In a machine of the class described, a pair of co- 55 acting dies for punching the side of a pail and forming a flange thereon, in combination with a pair of coacting finishing dies for inserting and securing an ear in said hole and means for presenting a pail to said dies successively, substantially as described.
7. In a machine of the class described, two sets of fin- 60 ishing dies and two sets of earing dies, in combination with means for actuating them successively, means for feeding ears to said earing dies and suitable pail feeding means, substantially as described.
8. In a machine of the class described, two sets of fin- 65 ishing dies and two sets of earing dies, in combination with means for actuating the same in succession, means for feeding ears to said earing dies, suitable pail feeding means and means for adjusting the sets of dies toward and 70 from each other to fit pails of different sizes, substantially as described.
9. In a machine of the class described, relatively adjustable punching and earing mechanisms adapted to operate on opposite sides of a pail, in combination with ear feeding means and a pail feeding device, substantially 75 as described.
10. In a machine of the class described, the combination of a pair of punching and flanging dies with a pair of ear affixing dies, means for feeding ears to said affixing dies, and centrally located means common to said ear affixing dies for operating them and other means for operating said punching dies, substantially as described. 80
11. In a machine of the class described, the combination of a pair of punching and flanging dies with a pair of ear affixing dies, means for feeding previously formed ears to said affixing dies, means for positioning a pail with respect to each said pair of dies and means for operating said pairs of dies successively, substantially as described. 85
12. In a machine of the class described, the combination of a pair of punching and flanging dies with a pair of ear affixing dies for fastening an ear in the pail, means for feeding previously formed ears to said affixing dies, means for operating said pairs of dies successively, and means for feeding a pail to said pairs of dies in the order named and for removing it from the path of the dies after said dies 90 have completed their cycle of operation, substantially as described. 95
13. In a machine of the class described, a pair of punching and flanging dies, a pair of ear affixing dies for fastening an ear in a pail, means for feeding previously formed ears to said affixing dies, means for operating said pairs of dies successively, a chuck plate adapted to receive a pail and means for actuating said chuck plate to move and hold the pail in operative position with said pairs of dies 100 successively, substantially as described. 105
14. In a machine of the class described, a pair of punching and flanging dies and a pair of ear affixing dies for fastening an ear in a pail, in combination with means for feeding previously formed ears to said affixing dies, means for operating said pairs of dies successively, a chuck plate 110 adapted to receive a pail, means for actuating said chuck plate to present a pail to said pairs of dies successively and for removing the pail from the path of the dies when said dies have completed their cycle of operation, substantially as described. 115
15. In a machine of the class described, a pair of punching and flanging dies and a pair of ear affixing dies for fastening an ear in a pail, in combination with means for feeding previously formed ears to said dies, means for operating said pairs of dies successively, a chuck plate 120 adapted to receive a pail, means for actuating said chuck plate to present the pail to said pairs of dies successively and for removing the pail from the path of the dies when said dies have completed their cycle of operation and means for automatically stopping the machine at the end 125 of its cycle, substantially as described.
16. In a machine of the class described, a pair of punching and flanging dies and a pair of ear affixing dies, in combination with a chuck plate adapted to receive a pail, means for operating said chuck plate to present the 130 pail to said pairs of dies successively, means for operating said pairs of dies successively, means for feeding previously formed ears to a point beneath said affixing dies, and means for elevating an ear to said affixing dies, substantially as described. 135
17. In a machine of the class described, a pair of punching and flanging dies and a pair of ear affixing dies for fastening an ear in a pail, in combination with means for operating said pairs of dies successively, pail feeding means for presenting a pail to said dies successively, means operable by said pail feeding means for feeding a previously formed ear to a point adjacent to said seaming dies and means for presenting said ear to the seaming dies, substantially as described. 140
18. In a machine of the class described, a pair of punching and flanging dies and a pair of ear affixing dies for fastening an ear in a pail, each comprising inner and outer die members, in combination with a drive shaft, a single device operated by said drive shaft for actuating said 145

- inner die members successively and cams geared to said drive shaft for operating the outer die members, means for feeding previously formed ears to said seaming dies, and means for presenting the pail to said dies successively, 5 substantially as described.
19. In a machine of the class described, a pair of punching and flanging dies and a pair of ear affixing dies, in combination with a chuck plate adapted to receive a pail to be eared, a drive shaft, suitable mechanism connecting 10 said shaft and said chuck plate whereby the latter is actuated to present the pail to said punching dies and said affixing dies successively, and suitable means for operating said dies in succession, substantially as described.
- 15 20. In a machine of the class described, a pair of punching and flanging dies and a pair of ear fastening dies, in combination with an ear feeding device, a chuck adjacent to said dies and adapted to receive a pail to be eared, a vertically reciprocating yoke supporting said chuck, a 20 drive shaft, a cam upon said drive shaft adapted to reciprocate said yoke and chuck plate whereby the latter is adapted to present pail to said pairs of dies successively, substantially as described.
21. In a machine of the class described, a pair of punching and flanging dies and a pair of ear affixing dies, means adjacent to said dies for feeding a pail first to said punching and flanging dies and then to said ear affixing dies, means for feeding ears to said ear affixing dies, a drive shaft, a vertically reciprocating device operable from 30 said shaft and adapted to actuate the inner members of said dies successively, and means for actuating the outer members of said dies successively, substantially as described.
22. In a machine of the class described, a pair of pail 35 earing mechanisms adapted to fasten ears to the opposite sides of a pail, and means for operating the same simultaneously, substantially as described.
23. In a machine of the class described, a pair of similar pail earing mechanisms adjustable toward or away from 40 each other and means for operating the same simultaneously, substantially as described.
24. In a machine of the class described, a pair of similar pail earing mechanisms mounted upon a suitable frame, means for operating the same to simultaneously affix previously formed ears to the opposite sides of a pail, and 45 means for feeding the ears to said mechanism, substantially as described.
25. In a machine of the class described, a pair of similar pail earing mechanisms mounted upon a suitable frame, 50 means for operating the same simultaneously, and means for automatically feeding previously formed ears to said mechanisms, substantially as described.
26. In a device of the class described, the combination of a pair of pail earing mechanisms mounted upon a suitable frame and means for operating the same simultaneously, 55 each said device comprising a pair of coating punching and flanging dies, a pair of ear affixing dies, and means for operating the same successively, substantially as described.
- 60 27. In a machine of the class described, the combination of a pair of similar pail earing mechanisms mounted upon a suitable frame and adjustable toward and away from each other, each said device comprising a pair of punching and flanging dies and a pair of affixing dies, means for 65 feeding ears to said finishing dies, and means for operating said dies successively, substantially as described.
28. In a device of the class described, the combination of a pair of similar pail earing mechanisms mounted upon a suitable frame with means for operating said mechanisms, 70 chuck plates adapted to receive a pail, and means for actuating said chuck plates to bring the pail into operative position with said earing mechanisms, substantially as described.
- 75 29. In a device of the class described, the combination of a pair of similar pail earing mechanisms mounted upon a suitable frame with means for operating said mechanism, chuck plates adapted to receive a pail, means for actuating said chuck plates to present a pail to said earing mechanisms, and means for automatically stopping the machine after the pail is eared, substantially as described. 80
30. In a device of the class described, two relatively adjustable pail earing mechanisms, each comprising a pair of coating punching and flanging dies and a pair of ear affixing dies and a mounting, in combination with means for operating said punching and affixing dies successively, 85 chuck plates adapted to receive a pail, and means for actuating said chuck plates to present a pail to said dies successively, substantially as described.
31. In a machine of the class described, a suitable table, in combination with a pair of pail earing mechanisms adjustable toward or from each other thereon, a single drive shaft, and suitable mechanisms connecting said drive shaft with said earing mechanisms for operating the same, substantially as described. 90
32. In a machine of the class described, the combination of a table with a pair of similar pail earing mechanisms upon said table, each said mechanism comprising a carrier, a pair of punching and flanging dies and a pair of ear affixing dies, a power shaft beneath said table, a vertically reciprocating device actuated from said power shaft for operating the inner members of said dies successively, vertical shafts driven from said power shaft and cams upon said vertical shafts for operating the outer members of respective dies, substantially as described. 95
33. In a machine of the class described, a pair of pail earing mechanisms adapted to fasten ears to the opposite sides of a pail simultaneously, in combination with a chuck plate for receiving a pail, a power shaft, suitable mechanism connecting said power shaft and said chuck plate to operate the latter and suitable mechanisms connecting said earing mechanisms and said power shaft to operate the former, substantially as described. 100
34. In a machine of the class described, a pair of relatively adjustable pail earing mechanisms adapted to fasten ears to the opposite sides of a pail, each said mechanism containing a pair of punching dies and a pair of ear affixing dies, in combination with a chuck plate adapted to receive the pail to be eared, a power shaft, suitable mechanism connecting said shaft and said chuck plate whereby the latter is actuated to present the pail to said punching and said affixing dies successively, and suitable means connecting said power shaft and said dies for actuating the latter, substantially as described. 115
35. In a machine of the class described, a pair of pail earing mechanisms mounted upon said table and adjustable toward or from each other thereon, each mechanism comprising a pair of punching dies, a pair of affixing dies and an ear feeding device, in combination with a frame whereon said mechanisms are mounted, a centrally located pail chuck, a vertically reciprocating cross-head beneath said table and supporting said chuck, a power shaft beneath said table, a cam upon said shaft for reciprocating said cross-head and chuck to present the pail to said punching and affixing dies successively, a vertically reciprocating double wedge member for actuating the inner members of said dies successively, a cam upon said power shaft for actuating said wedge member, and a plurality of cams driven from said power shaft for actuating the outer die members, substantially as described. 120
36. In a machine of the class described, a table, in combination with a pair of pail earing mechanisms relatively adjustable thereon, each said mechanism comprising a pair of punching dies and a pair of ear affixing dies; a chuck adapted to receive a pail to be eared; a drive shaft and means for actuating said dies and chuck from said drive shaft, substantially as described. 140
37. In a machine of the class described, a table, in combination with a pair of pail earing mechanisms adjustably mounted thereon, each mechanism comprising a pair of punching dies, a pair of ear affixing dies, an ear feeding device and an ear magazine; a chuck plate adjacent to said mechanisms to receive the pail to be eared; a drive shaft beneath said table; suitable mechanism connecting said chuck plate and said shaft whereby the former 145
- 150

is actuated to present the pail to said punching and affixing dies successively; means for operating said magazines from said chuck plate, and means for actuating said dies and said ear feeding devices, substantially as described.

38. In a machine of the class described, a pair of ear affixing dies and the mountings therefor, in combination with means for operating said dies, an ear feeding device co-acting therewith, a pail chuck and means for actuating said chuck in such manner that the pail is lowered in time

to assist in guiding an ear into position between said dies, substantially as described.

In testimony whereof, we have hereunto set our hands, this 30th day of March, 1907, in the presence of two subscribing witnesses.

PETER W. FULFORD.

CHARLES STECHER.
